UNITED STATES PATENT OFFICE.

JOHN P. FEENEY AND JOHN H. NEWHARD, OF ALLENTOWN, PENNSYLVANIA.

WORKHOLDER.

Application filed November 23, 1921. Serial No. 517,247.

To all whom it may concern:

Be it known that we, JOHN P. FEENEY and JOHN H. NEWHARD, citizens of the United States, and residents of Allentown, in the 5 county of Lehigh and State of Pennsylvania, have invented a new and useful Improvement in Workholders, of which the following is a specification.

Our invention relates to work holders and 10 its all important object is to provide a work holder particularly adapted to hold piston rings while filing the same for proper fitting on the piston although not restricted to such use.

15 A second important object of the invention is to provide a combination device which will hold the piston ring in a horizontal position for filing the upper and lower surface thereof and after such operation will hold the piston ring in a vertical position while the ends thereof are lapped or filed.

20 It is another object of the invention to provide a work holder which includes a pair of oppositely movable carriages and sets of supplemental gripping members, one set of which being adapted for use in holding annular bodies such as piston rings and the other set being adapted for holding a 25 rectangular body.

With the preceding and other objects and 30 advantages in mind, the invention consists of the novel combination of elements, constructions and arrangement of parts to be set forth in detail, claimed and illustrated in the accompanying drawings, wherein:

Figure 1 is a perspective of our improved work holder.

Figure 2 is a perspective of one of the 40 movable carriages embodied in the invention.

Figure 3 is a transverse sectional view taken on line 2—2 of Fig. 1.

Figure 4 is a plan view of a modified embodiment of the invention, parts being broken away.

Figure 5 is a perspective of one of the gripping elements for use in holding an annular body.

50 Figure 6 is a similar view of one of the gripping members for holding a rectangular body, and

Figure 7 is an enlarged fragmentary plan view illustrating the device as used to hold 55 a rectangular object.

Referring to the drawing in detail where-

in corresponding characters of reference designate corresponding parts throughout the several views, the numeral 5 designates a cast metal rectangular base having a 60 transverse T-shaped groove or counter-sink 6 therein adjacent one end thereof. As shown in Fig. 1 the groove or counter-sink 6 is closed at one end thereof and constitutes a bearing section 7. Extending longitudinally 65 in the groove or counter-sink 6 is a hand operated screw 8 having one-half of its length provided with right-hand threads 9 and the other half of its length provided with left-hand threads 10. One end of this 70 screw is journaled between the bearing sections 7 and the upper removable bearing section 11, the latter being secured to the base 5 by fastenings 12.

Arranged in opposed relation and adapted 75 for longitudinal movement toward and away from each other in the groove 6 is a pair of T-shaped blocks or carriages 13. These blocks or carriages 13 are provided with horizontally threaded bores 14 through 80 which the threaded stem 8 passes. Each of the blocks or carriages 13 has formed with, at its upper end and at the rear edge thereof, a rectangular extension 15 while the upper surface of these blocks or carriages are 85 flush with the upper surface of the base 5 and constitutes work rests 16.

For cooperation with the carriages or blocks 13 there is provided a pair of opposed and longitudinally bowed resilient clamps 17 90 to the outer face of a longitudinal centre of which a T-shaped member 18 is secured as shown in Fig. 5. The vertical legs 19 of these T-shaped members 18 are rectangular 95 in cross section and are removably received in cross section and are removably received in rectangular recesses 21, in the surfaces 16 of the blocks or carriages 13. With the legs 19 thus engaged the horizontal legs of the T-shaped members will abut the vertical 100 extensions 15 and thereby prevent the resilient clamp 17 from becoming distorted should the blocks or carriages 13 be moved too close together. By the provision of these resilient clamps 17 it will be obvious that they will conform to various sized piston 105 rings. In order to indicate when the surfaces of the piston ring T are level, a surface plate 22 is provided in the base 5.

A vise 23 is carried by one end of the base 5 and includes a pair of horizontal jaws 24 110 which holds the piston ring in a vertical position as shown in dotted lines in Fig. 1 so

that the ends thereof may be filed or lapped. A hand operated screw 25 is associated with the vise 23 for moving the jaws into clamping engagement with the piston ring.

5 When it is desired to hold a rectangular object on the carriages 13 as shown in Fig. 7 rectangular jaws 26 having lugs 27 are arranged on the blocks or carriages 13 with the lugs engaged in the recesses 21.

10 It is to be understood that the form of our invention herein shown and described is to be taken as a preferred example of the same and that various changes in the shape, size and arrangement of parts may be resorted to without departing from the spirit of the invention or the scope of the subjoined claims.

Having thus described our invention what we claim as new and desire to secure and 20 protect by Letters Patent of the United States is:

1. A work holder comprising a horizontal base upon which the work to be held rests and provided with a transverse groove, carriages adjustable longitudinally in the groove, a common means for moving the carriages away and towards each other, and resilient longitudinally bowed gripping members carried by the carriages adapted 25 to embrace an annular object.

2. A work holder comprising a base having a longitudinal groove a pair of rectangular carriages movable in the groove, means for moving the carriages away and toward each other, each of the carriages being provided with a recess in its upper face and an opposed longitudinally bowed resilient gripping element for each carriage and each including a member removably received in one of the recesses. 35

3. A device for holding fragile annular bodies including a base, a pair of opposed resilient gripping elements mounted on the base, and means for moving the same in opposite directions. 40

4. A device for holding fragile annular bodies including a base upon which the article to be held is adapted to rest, a pair of longitudinally bowed resilient opposed gripping elements resting on the base, and means 45 for adjusting the gripping elements in opposite directions.

5. A piston ring holder comprising a base, a pair of longitudinally bowed resilient gripping elements arranged on the base and 50 adjustable in opposite directions, the gripping elements being of less vertical thickness than the piston ring held therebetween.

JOHN P. FEGELY.

JOHN H. NEWHARD.
